(57) **CLAIM**

The ornamental design for a footwear outsole, as shown and described.

DESCRIPTION

FIG. 1 is a perspective view of a footwear outsole showing my new design.

FIG. 2 is a right side elevational view thereof;

FIG. 3 is a left side elevational view thereof;

FIG. 4 is a bottom plan view thereof;

FIG. 5 is an enlarged cross sectional view taken on line 5—5 of FIG. 4;

FIG. 6 is a front elevational view of the footwear outsole;

FIG. 7 is a rear elevational view thereof; and,

FIG. 8 is a top plan view thereof.

The broken lines showing the inside surface of FIG. 5 is understood to represent the portion of the design that forms no part of the claim. The broken lines around the perimeter of the sole in FIGS. 7 and 8 are understood to form the boundary of the design, with the line itself and the area within, forming no part of the claim.

The heavy solid black lines across FIGS. 1 and 4 are understood to represent shading.
